UNITED STATES PATENT OFFICE.

ROBERT D. DUNCAN, JR., OF EAST ORANGE, NEW JERSEY, ASSIGNOR TO WIRED RADIO, INC., OF NEW YORK, N. Y., A CORPORATION OF DELAWARE.

DUPLEX RADIOTELEPHONE SYSTEM.

Application filed July 24, 1925. Serial No. 45,948.

My invention relates broadly to radio telephony and more particularly to a system of duplex radio telephony.

One of the objects of my invention is to provide a system of radio telephony in which transmission and reception may be carried on simultaneously without mechanical switching means for rendering the transmitter inoperative when receiving and vice versa.

Another object of my invention is to provide a duplex radio telephone system in which simultaneous two way communication may be conducted with closely related transmitting and receiving antennæ without interference from side talk in the receiving system.

Still another object of my invention is to provide a polyphase system of radio transmission in which energy derived from one of the phases of the polyphase system is utilized to affect a local receiving circuit to balance out the disturbing influences of the transmitting system upon the local receiving circuit.

A further object of my invention is to provide a radio telephone system in which simultaneous transmission and reception on closely adjacent antennæ may be conducted by means of the use of three phase high frequency currents at the transmitting apparatus.

My invention will be more clearly understood from the specification hereinafter following by reference to the accompanying drawings, in which:

Figure 1 is a wiring diagram showing a transmitting and receiving station embodying the principles of my invention; Fig. 2 represents at A, B, and C vector diagrams of current, magnetic flux and voltage, in the circuits of the communication system; and Fig. 3 illustrates a circuit diagram of a complete duplex or simultaneous two way transmitting and receiving system showing the application of my invention.

Heretofore in the art duplex systems of radio telephony on the same or on closely adjacent antennæ have been relatively com-

plicated and have depended largely upon "bridge" or balanced circuits in which the effect of the transmitting circuit is neutralized or balanced in so far as it acts upon the receiving apparatus. Due to relatively high power of a normal high frequency radio telephone transmitter and to the extreme sensitivity of the receiving equipment without such balancing circuits, even with the transmitting and receiving frequencies fairly widely separated, the intense magnetic and static fields established by the transmitting current tend to paralyze the receiving apparatus and render it practically impossible to simultaneously transmit and receive on the same or on closely adjacent antennæ.

By my present invention I provide a three phase high frequency generating system with connections for impressing a portion of the high frequency energy upon a radiating circuit. The receiving system is located closely adjacent the transmitting apparatus and a link circuit is provided between the transmitting system and the receiving system for impressing upon the receiving system a portion of the high frequency energy from the transmitting circuit. The receiving system has a normal voltage induced therein by direct action from the transmitting antenna. By virtue of the peculiar phase relations existing in a three phase system, the high frequency energy which is arbitrarily introduced into the receiving system from the transmitting system has its time phase in direct opposition to the time phase of the energy existing in the receiving circuit by action from the transmitting circuit as a result of which interfering currents in the receiving system are neutralized and the receiving circuit functions without interference from the local transmitting system. In this manner simultaneous transmission and reception on closely adjacent antennæ may be conducted without mechanical switching means between the transmitting and receiving apparatus.

The advantages of being able to simul-

5 simultaneously transmit and receive in radio telephony, that is in the same manner as with the normal wire telephone, are well known to those familiar with radio art. Where 10 conditions impose the use of closely adjacent transmitting and receiving antennae such as on shipboard or on an airplane or airship, the additional advantages are manifest.

10 Referring to Fig. 1 of the drawings, reference character 1 represents a source of modulated three phase high frequency energy, 2, 3, 4, inductances shown for example connected in Y to each phase of the 15 high frequency source 1. Reference numeral 5 designates a transmitting antenna connected in series with inductances 6, 7, to ground 8. Inductances 6, 7, are shown inductively coupled to inductances 2, 3. Reference character 9 shows a receiving antenna connected in series with inductances 10 and 11 to ground 8. Inductively coupled with inductances 4 and 11 is series circuit 12 comprising inductance 13, variable capacity 20, 25 inductance 15 and variable resistance 16. This circuit is shown shielded at 17 from both the circuits containing inductances 4 and 11, the shield being grounded at 8, at a suitable point. Inductively coupled with inductance 10 is the receiving circuit 18, comprising inductance 19, capacity 20, a vacuum tube detector circuit represented in its entirety by 21 and shown containing telephone receivers 22, in the output circuit. Inductance 10 is shielded from inductance 19 by metallic shield 23, shown grounded at 8. While I have illustrated the inductances 2, 3, and 4 as connected in Y it will be understood that the inductances may be connected 30 in A. The transmitting antenna 5 may be closely adjacent the receiving antenna 9.

45 In Fig. 3 I have illustrated a complete circuit diagram of a duplex transmitting and receiving system. The three phase high frequency current is developed for example by a circuit arrangement which is more particularly described in my co-pending application Serial Number 1,374, filed January 5, 1925, Patent No. 1,578,881. Reference is made to my co-pending application for a complete description of the three phase high frequency current generator. For the purpose of clearly explaining the operation of the duplex system of the present application, it will be sufficient to observe that a single phase high frequency current generator of any suitable type, illustrated here by reference character 25 as of the self-excited electron tube type, is connected as illustrated by reference character 48 to the tuned system 26 which is coupled through the Y connected inductance system 27 as represented by brace I with electron tube high frequency power amplifiers 28, 29, and 30, the output circuits of which impress polyphase high fre-

quency signaling energy on the transmitting antenna system 5 through coupling coils 2—6 and 3—7. The coupled system 26 serves to set up a rotating high frequency magnetic field which is picked up by the inductances 27 disposed at the proper angles with respect to coils 26 for setting up currents in coils 27 displaced in phase from each other by 120°. Energy delivered from amplifier circuit 30 is impressed upon the link circuit 12 through coupling coils 4—13 and is in turn impressed upon the receiving system through coupling coils 15—11. Modulation of the system is secured through parallel connected tubes 43, 44 and 45 controlled from microphone 47 connected in the input circuit of the amplifier, the output of the tubes 43, 44, and 45 being connected across the output circuits of each of the tubes 28, 29, and 30 for controlling the output thereof with respect to the antenna system 5 of link circuit 12. The receiving system is coupled to the antenna circuit 9 as explained in connection with Fig. 1. It is understood that ground connections designated throughout by numeral 8 indicate a common point of connection in the circuits.

50 In the operation of the system, three phase high frequency currents i_1 , i_2 , i_3 are generated by the three phase source 1 and have the relationship as represented in vector diagram A of Fig. 2 where they are displaced in time phase by 120°. The vectors are assumed to rotate in a counter clockwise direction. Current i_1 establishes a magnetic field ϕ_1 , shown vectorially in Fig. 2 (B) in time phase with i_1 , and which links with inductances 2 and 6 as indicated by a dotted line in Fig. 1. Magnetic field ϕ_1 induces a driving voltage e_{1T} in inductance 6, lagging in time phase as shown in Fig. 2 (B) by 90°. The antenna circuit 5 is tuned to resonance to the frequency f_T of the source 1 and the resulting current i_{1T} which tends to flow under the action of voltage e_{1T} is substantially in phase with e_{1T} as shown in Fig. 2 (B). The same is true with the magnetic field ϕ_2 linking inductances 3, 7, as shown in dotted line in Fig. 1, produced by current i_2 and in phase therewith, tending to cause the current i_{2T} , 120° lagging i_{1T} , to flow in the antenna circuit. The resultant current i_T , which flows in the transmitting antenna 5 under the combined action of voltages e_{1T} and e_{2T} , is the vector sum of i_{1T} and i_{2T} , which is shown in Fig. 2 (B) as the vector i_T lagging i_{1T} by 60°. Reference is now made to Fig. 2 (C) considered in conjunction with Fig. 1. The resultant transmitting antenna current i_T produces a magnetic field ϕ_T in phase with i_T and surrounding the antenna. This field impinges upon the receiving antenna 9, closely adjacent to the transmitting antenna, and induces therein driving voltage e_{TR} 130

lagging ϕ_T in time phase by substantially 90° . Now the receiving antenna circuit is adjusted to resonance to the receiving frequency f_R which differs in value from f_T . For frequency f_R the reactance of antenna circuit 9 is therefore substantially zero. For illustration it is here assumed that the transmitting frequency f_T is greater than the receiving frequency f_R and hence at this frequency antenna circuit 9 behaves as an inductive reactance. The current which the voltage e_{TR} tends to cause to flow will therefore lag e_{TR} in time phase, shown in Fig. 2 (C) by the vector i_{TR} lagging e_{TR} by the angle θ . If f_T were less than f_R , current i_{TR} would lead e_{TR} . Now transmitting current i_3 establishes magnetic field ϕ_3 which does not act upon the antenna circuit 5, but which links with inductance 13 of circuit 12 as shown in dotted lines in Fig. 1. It induces in this inductance driving voltage e_3 , lagging ϕ_3 , by 90° . By means of variable capacity 14, circuit 12 is tuned substantially to resonance to frequency f_T in which case the current i_1 , which flows will be approximately in phase with e_3 . Current i_1 establishes magnetic field ϕ_1 , in phase therewith, which links inductances 15 and 11 and induces in the latter, i. e., in the receiving antenna circuit 9, driving voltage $e_{1,R}$. This voltage is practically 180° out of phase with voltage e_{TR} induced directly in the receiving antenna by the transmitting antenna. The current which tends to flow in circuit 9 under the action of voltage $e_{1,R}$ will lag $e_{1,R}$ by the angle θ , and is represented by $i_{1,R}$. The amplitude of $e_{1,R}$ and hence $i_{1,R}$ is regulated by means of coupling between inductances 4-13 and 11-15, and by variation of capacity 14 and resistance 16. With the amplitude of $e_{1,R}$ equal to that of e_{TR} , and with its time phase in opposition thereto, it will be observed that no current will flow in receiving antenna circuit 9 due to current flowing in transmitting antenna 5. Shielding of the link circuit 12 and of the receiving circuit is desirable as it protects the circuits so shielded from electrostatic effects of the transmitting current and enables the obtaining of more perfect elimination of all induced effects in the receiving circuits.

By the methods and circuits just disclosed simultaneous radio telephone transmission and reception on antennae in close proximity of each other may be conducted with suitable transmitting and receiving frequencies without either complete paralyzing of the local receiving apparatus by the local transmitter or giving rise to excessive and disturbing side tones. In fact the absence of side tones may be so complete, that the operator will be unable to hear any of his own conversation, which for many

reasons is often an undesirable condition so 65 that the balance obtained at link circuit 12 may be arbitrarily disturbed so as to yield side tones of the required intensity.

I have illustrated only one method of modulation which may be employed in the 70 transmitting system, but it will be understood that grid modulation or other arrangements of circuits may be provided for effecting the transmission of signals. It will also be understood that I may employ other arrangements of detector circuits and that a crystal detector may be used in lieu of the tube detector illustrated herein, or various arrangements of amplification systems may be provided at the receiver for reproducing 80 the desired signals.

While I have described my invention in certain particular embodiments, I desire that it be understood that modifications may be made and that no limitations upon the invention are intended other than those imposed by the scope of the appended claims. 85

What I claim and desire to secure by Letters Patent of the United States is as follows:

1. A duplex radio transmission and reception system comprising in combination a source of three phase high frequency electrical energy, a transmitting antenna system, means for exciting said antenna system with 95 two phases of said source, a receiving system and connections between the remaining phase of said source of high frequency energy and said receiving system for impressing the high frequency electrical energy of 100 said remaining phase upon said receiving system for neutralizing the effects of the transmitting system upon said receiving system.

2. A duplex radio telephone transmission 105 and reception system comprising in combination a source of modulated three phase high frequency electrical energy, a transmitting antenna system, means for exciting said antenna system with two phases of said source, a receiving system and connections between said source of high frequency energy and said receiving system for impressing the high frequency electrical energy from 110 the remaining phase of said source upon said receiving system for neutralizing the effects of the resultant current derived from the first mentioned two phases of said source. 115

3. A radio telephone communication system comprising in combination a transmitting and receiving system in close proximity to each other, a source of three phase electrical energy, means for impressing energy from two phases of said three phase source upon said transmitting system, and means for impressing energy from the third remaining phase of said source upon said receiving system for neutralizing the effects 125

in said receiving system of the high frequency electrical energy transmitted by said transmitting system.

4. A radio communication system for duplex operation comprising in combination a transmitting circuit, a receiving circuit, a source of three phase high frequency electrical energy, means for impressing two phases of said energy on said transmitting circuit, and means for impressing the remaining phase of said electrical energy upon said receiving circuit for balancing the effects therein of the vector sum of currents derived from said transmitting circuit.
5. A radio communication system comprising in combination a transmitting circuit, a receiving circuit located in proximity thereto, a source of three phase high frequency electrical energy, means for impressing two phases of said energy upon said transmitting circuit, and separate means for impressing the remaining phase of said energy upon said receiving circuit for establishing in said receiving circuit current having its time phase in opposition to the vector sum of currents existent in said receiving circuit by reason of the influence of said transmitting circuit upon said receiving circuit.
6. A duplex radio transmission and reception system comprising in combination a source of three phase high frequency electrical energy, a transmitting system, means for exciting said transmitting system with two phases of said energy, a receiving system, a link circuit interconnecting the other of the phases of said source with said receiving system for impressing high frequency electrical current upon said receiving system in phase opposition to the vector sum of currents otherwise existent therein from said first mentioned two phases for neutralizing the effects of the transmitting system upon said receiving system.
7. A radio telephone transmitting and receiving system comprising in combination, a source of modulated three phase high frequency current, at least one inductance electrically associated with each phase of said source and interconnected in a three phase manner, a transmitting antenna system containing a plurality of inductances, two of said last named inductances being inductively coupled independently with two of said first named inductances, a receiving antenna system in proximity to said transmitting antenna system, a plurality of inductances in series connection with said receiving antenna, a signal translating and responsive means associated with one of said receiving antenna inductances, a link circuit containing at least two inductances in series connection, one of said link circuit inductances inductively coupled to the remaining of said three first mentioned in-

ductances, the remaining of said link circuit inductances inductively coupled with remaining of said two receiving antenna inductances, the adjustment of said transmitting and receiving antenna systems in combination with that of said link circuit by virtue of the opposing phase relations of the voltages established in said receiving antenna system by the current in said transmitting antenna and through the means of said link circuit providing a means of effecting simultaneous transmission and reception without the said signal translating and responsive means being rendered inoperative or its sensitivity substantially influenced from the induced effects in said receiving antenna system caused by current existent in said transmitting antenna system.

8. A radio telephone transmitting and receiving system comprising in combination a source of three phase high frequency current, a plurality of electron tube circuits corresponding in number to the number of phases of said source, an input circuit for each of said electron tube circuits, inductances in each of said input circuits electrically associated with each phase of said three phase source, an output circuit for each of said electron tube circuits, said output circuits each containing an inductance, a transmitting antenna system inductively coupled to two of said output inductances, means for effecting telephonic modulation of the high frequency energy existent in said electron tube circuits, a receiving antenna system in proximity to said transmitting antenna system and containing a plurality of inductances, a signal translating and responsive means electrically associated with one of said last mentioned inductances, a link circuit containing a plurality of inductances, said link circuit inductively coupled to the third of said output inductances of said electron tube circuits and to the other of said plurality of receiving antenna system inductances, the adjustment of said transmitting and receiving antenna systems and of said link circuit by virtue of the opposing phase relations of the voltages established in said receiving antenna system by the current in said transmitting antenna and through the means of said link circuit providing a means of effecting simultaneous transmission and reception without said signal translating and responsive means being rendered inoperative or its sensitivity substantially influenced from the induced effects in said receiving antenna system caused by current existent in said transmitting antenna system.

9. A radio telephone communication system comprising in combination transmitting and receiving antenna systems in proximity to each other, a source of unmodulated three phase electrical energy, means for impress-

ing energy from two phases of said three phase source upon said transmitting antenna system, means for impressing energy from the third remaining phase of said source upon said receiving system for neutralizing the effects in said receiving antenna system of the high frequency electrical energy transmitted by said transmit-

ting antenna system, and means interposed between said three phase source and said means for impressing energy from said source upon said transmitting and receiving antenna systems for effecting telephonic modulation of said three phase high frequency electrical energy. 10

ROBERT D. DUNCAN, JR.
